UNITED STATES PATENT OFFICE.

HENRY WEST, OF GALESBURG, ILLINOIS.

TROLLEY.

No. 832,712.

Specification of Letters Patent.

Patented Oct. 9, 1906.

Application filed July 20, 1903. Serial No. 166,292.

To all whom it may concern:

Be it known that I, HENRY WEST, a citizen of the United States, residing at Galesburg, in the county of Knox and State of Illinois, have invented certain new and useful Improvements in Trolleys, of which the following is a specification.

The present invention relates partly to the construction of the trolley-wheel and partly to the construction of the fittings by which it is secured to the trolley-pole or other supporting device.

It consists in the features of novelty that are hereinafter described with reference to the accompanying drawings, which are made a part hereof, and in which—

Figure 1 is an elevation of a trolley and its accessories embodying the invention, a portion of the cup-shaped fitting at the upper end of the trolley-pole being broken away. Fig. 2 is a sectional elevation of the trolley in a diametrical plane, portions of the "harp" being shown in section. Fig. 3 is a sectional elevation of the trolley in a central plane at right angles to its axis.

The body of the trolley is made up of two principal parts A and A' in the form of circular disks having centrally-located threaded openings and having near their peripheries annular flanges a and a', which when the parts are assembled telescope with each other and form a tight joint. The flanges a and a' are a sufficient distance from the peripheries of the disks to leave a peripheral groove in which is arranged a ring B, preferably of copper, which contacts with and takes the current from the wire. This ring may contact directly with the flange a, but preferably it is supported by screws C, which pass through the ring B and flanges a and a' into the ends of a bar or spoke D, which is located within the hollow chamber E of the trolley and is integral with a shaft F, with which the disks A and A' have threaded engagement. The screws C and the shaft F constitute the means for connecting the two disks. The screws also serve as conductors for conveying the current from the ring B to the spoke D, from which latter it is taken by brushes G, having contact with a collecting-ring H, carried by a shaft I, said shaft being located within the shaft F and ball-bearings J being arranged between them. The central part of the diametrical bar D and of the shaft F is cut away to accommodate the collecting-ring H and permit the brushes to have contact with it at

diametrically opposite points. The collecting-ring is rigidly secured to the shaft I by means of a pin h. The ends of the shaft I pass through the sides K of the harp and have nuts L turned onto them for the purpose of holding the parts in place. The harp preferably consists of two parts K, which at their lower ends are jointed together by means of a pin M, passing through the cup-shaped fitting N, which is fixedly attached to the extremity of the pole O. This permits the harp to oscillate slightly in a direction transverse to the line of travel in order that the trolley may follow deflections in the contacting wire. This movement of the harp is, however, limited by lugs P on its sides, which are adapted to contact with the top of the fitting N.

At its sides the spoke D contacts with the inner faces of the disks A and A', while at its ends it contacts with the inner surface of the flange a' at diametrically opposite points, thus dividing the chamber E into two equal parts. In order that these two parts may communicate with each other, notches d are formed in the ends of the spoke. The chamber E is also used for the purpose of carrying the lubricant, so that the bearing may at all times be supplied with the necessary quantity of oil. In practice it is proposed to charge the chamber with only a very small quantity of oil, which under the influence of centrifugal force will distribute itself evenly over the interior surface of the flange a' while the trolley is revolving and which when the trolley is at rest will find its way to the bearing and to the collecting-ring.

The object in leading the current through the brushes, the collecting-ring, and the central shaft is to avoid burning out the ball-bearings. It will be understood that if the current were led through the ball-bearings a loose ball would cause sparking and would quickly destroy the bearings.

What I claim as new, and desire to secure by Letters Patent, is—

1. A trolley having an internal chamber, a collecting-ring within the chamber, means for conducting the current to the collecting-ring, said means consisting of a diametrical bar or spoke and brushes carried thereby and contacting with the collecting-ring, substantially as described.

2. A trolley having a peripheral groove and an internal chamber, a ring arranged in the groove and adapted to contact with the

trolley-wire, a collecting-ring within the chamber and means for conducting the current to the collecting-ring, said means including screws contacting with the peripheral ring, a diametrical bar or spoke contacting with said screws and brushes carried by the bar or spoke and contacting with the collecting-ring, substantially as described.

3. A trolley having two disks with central openings, telescoping flanges by which the disks are held apart to provide an internal chamber, a central shaft, a collecting-ring on said shaft and brushes within the chamber for conducting the current to the collecting-ring, substantially as described.

4. A trolley having two disks provided with telescoping annular flanges by which they are spaced apart to provide an internal chamber, a removable ring surrounding the outer flange and located between the peripheries of the disks, a diametrical bar arranged within the chamber, brushes carried by the bar, a collecting-ring with which the brushes contact and a shaft carrying the collecting-ring, substantially as described.

5. The combination with a trolley-wheel, of a harp by which it is carried, said harp being made of two parts or sides, a cup-shaped fitting fixedly attached to the end of the trolley-pole, into which the lower ends of said

two parts or sides extend, a pivot-pin supported by said fitting, in a position parallel with the line of travel, upon which the lower ends of said parts or sides are pivoted, clearance being left between the sides of the harp and the fitting, whereby the harp as a whole may be oscillated in a direction transverse to the line of travel, or its two sides moved toward and from each other for putting the trolley-wheel in place or removing it from its position between the two sides, the two sides of the harp being adapted to contact with the sides of the fitting for limiting its oscillation, a shaft passing through the trolley and the two sides of the harp, and means on said shaft for holding the two sides of the harp together, substantially as described.

6. A trolley having two disks with central openings, telescoping flanges by which the disks are held apart to provide an internal chamber, a central shaft, a collecting-ring, on the shaft, ball-bearings about said shaft, and brushes within the chamber for conducting the current to the collecting-ring, substantially as described.

HENRY WEST.
